INVENTOR

BY Victor J. Evans

ATTORNEY

WITNESS:

F. A. Ackerman Jr.

UNITED STATES PATENT OFFICE.

CHARLES M. GROS, OF KLOTZVILLE, LOUISIANA.

LOADER.

Application filed August 1, 1923. Serial No. 655,105.

This invention relates to a cane loader, the general object of the invention being to provide means whereby it may be attached to a tractor and the drums of which can be actuated from the tractor.

Another object of the invention is to provide a boom which is rotatably connected with the supporting frame and which is also pivoted to the frame so that it can be raised and lowered.

A further object of the invention is to provide means for making the "grab" capable of being used for digging ditches and the like as well as for handling cane and the like.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view showing the invention attached to a tractor.

Figure 2 is a section on line 2--2 of Figure 1.

Figure 3 is a plan view with parts in section.

Figure 4 is a section on line 4--4 of Figure 3.

Figure 5 is a section on line 5--5 of Figure 3.

Figure 6 is a sectional detail view through one of the drums.

Figures 7 and 8 are detail views of the brake mechanism for the drums.

Figure 9 is a sectional view through the grab and its connecting ropes.

Figure 10 is an elevation of the grab.

Figure 11 is a side view with the grab in open position.

Figure 12 is a view showing an attachment for the grab.

In these views, 1 indicates a frame which has its rear part supported by the wheels 2, the spindles 3 of which are pivotally connected with the axle 4, a connecting bar 4' having its ends connected with the spindles so that the wheels 2 will trail the tractor.

55 A tongue 5 connects the axle with the draw bar of the tractor which is shown at A.

The front part of the frame has the depending pieces 6 which are connected with the rear axle of the tractor, as shown at 7. A tower 8 is carried by the rear part of the frame and a double pulley 9 is located at the top of the tower.

An upright frame 10 is connected with the front part of the supporting frame and a brace 11 connects this frame 10 with the tower. A turn-table 12 is carried by the frame 10 and a boom 13 has its lower end pivotally secured to the center of the turn-table, as shown at 14.

The boom is connected with the brace by the cable 16 so that its inclination may be adjusted by lengthening or shortening the cable. A double pulley 17 is carried by the upper end of the boom. Drums 18 and 18' are rotatably mounted on a shaft 19 which is journaled in the supporting frame and which is connected by gears 20 with a stub shaft 21.

Shaft 19 is adapted to be driven from the tractor by means of the chain 22 and the sprockets 23. Cables 24 and 24' are connected with said drums and these cables pass over the pulleys 9 and 17 and are connected with the grab 25.

This grab consists of the shaft 26, the pairs of jaw members 27, pivotally mounted upon the shaft, and having their upper ends connected together by the rods 28 and the bars 29 and 29' which are connected with the cables 24 and 24'.

Flexible members 30 connect the bar 29 with the shaft 26 and flexible members 31 connect the bars 29 with one of the rods 28. Flexible members 32 connect a shaft 32', on one of the jaw members, with the bar 29'.

The parts are so arranged that when the weight of the grab is carried by the cable 24, which is connected with the bar 29, the jaw members will close but when this cable is slackened and the weight comes upon the cable 24' one set of jaw members will be moved upwardly and thus the jaw members will be open so that the grab can grip the pile of cane.

In order to make the grab capable of handling dirt I provide a pair of shovel attachments 33 which are provided with sockets for receiving the ends of the jaw members and which are attached to said members by the bolts 34. When the grab is provided with these attachments the apparatus can be used for cleaning out ditches and the like.

The drums are adapted to be connected with and disconnected from the shaft 19

by the clutch means 35, which are operated from the levers 36 through the connections 37. Brake means 38 are associated with the clutch means, the spring actuated band 39 of each brake means being arranged with a pair of cam projections 40 for engaging cam-shaped recesses 41 on the shaft 42 to which the brake arm 43 is attached. These parts are so arranged that when the clutches are moved into inoperative position the brakes will be applied to the drums and vice versa. The clutch and brake means will permit the cables 24 and 24' to be manipulated independently of each other or together, as desired. The turn-table is actuated by means of the cable 44 which engages a groove in the table and which after passing over guiding pulleys 45 has its ends connected with the drums 46 on a shaft 47. The cable is oppositely wound on said drums so that as it is being slackened off of one drum it is being wound upon the other. The shaft 47 is provided with a sliding clutch 48, operated by a handle 49 and provided with a pair of friction wheels 50 for engaging a friction wheel 51 on the stub shaft 21. Thus the shaft 47 can be rotated in either direction from the shaft 21, by moving the handle 49 in the proper direction.

From the above it will be seen that the grab can be raised and lowered and opened

and closed by the drums and that the boom can be swung to any desired position by means of the drums 46. This will permit the load to be dropped in wagons and the like.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination, a base, standards rising therefrom adjacent one end thereof, an inverted U-shaped support arranged adjacent the other end thereof, a turn table mounted on the support, a boom pivoted centrally on said table and projecting upwardly and outwardly therefrom, means for rotating said table, a diagonally arranged brace rod terminally connected with the upper ends of said standards and said support, a brace connecting said rod and boom, pulleys supported by the standards and the outer end of said boom, and a cable trained over said pulleys as and for the purpose specified.

In testimony whereof I affix my signature.

CHARLES M. GROS.
